ACCUMULATOR BIN FOR GRAIN CLEANING MACHINES

Filed May 29, 1930.

UNITED STATES PATENT OFFICE

JOHN W. HOEFLING, OF CHICO, CALIFORNIA, ASSIGNOR TO HOEFLING BROS. INC., OF CHICO, CALIFORNIA

ACCUMULATOR BIN FOR GRAIN-CLEANING MACHINES

Application filed May 29, 1930. Serial No. 457,377.

This invention relates to certain new and useful improvements in accumulator bins for grain cleaning machines and the like.

The primary object of the invention is to provide an accumulator bin for grain cleaning machines wherein the grain dropped into a hopper and conveyed to a point for discharge into a machine is controlled in its flow to the machine with an accumulator bin to receive excess grain delivered to the machine for return to the hopper, permitting the regulation of feed at the machine rather than at the elevator boot and permitting an operator to perform other duties while the grain collected in the accumulator bin is returned to the hopper for re-delivery to the machine by the elevator construction. Further, it eliminates the necessity for a supply bin above the machine to secure a uniform feed, permitting the bin to be at or below the level of the machine.

With the above and other objects in view that will become apparent as the nature of the invention is better understood, the same consists in the novel form, combination and arrangement of parts hereinafter more fully described, shown in the accompanying drawing and claimed. While the form herein described refers specifically to its use with a grain cleaning machine, it is of course adapted to use with other types of machines handling granular material, such as grinders, clippers, separators, etc.

In the drawing:—

Figure 1 is a fragmentary side elevational view, partly in section, showing an accumulator bin for grain cleaning machines embodying an endless conveyor for carrying the grain from the upper end of the elevator to the point of entry into cleaner with the excess grain returned from this point to the accumulator bin for return into the grain hopper;

Figure 2 is a vertical cross-sectional view taken on line 2—2 of Figure 1, showing the manually controlled gate between the grain hopper and elevator and the discharge opening from the accumulator bin into the grain hopper; and

Figure 3 is a fragmentary side elevational view, partly in section with the endless con-

veyor omitted and the grain gravitationally descending to the points of delivery into the cleaner and the surplus returning to accumulator bin also by gravity.

The invention relates to devices for supplying grain to a grain handling machine. The reference numeral 1 designates a grain elevator having a grain receiving hopper 2 associated with the rear side thereof at the lower end, the entrance or passage of grain from the hopper 2 into the elevator being accomplished by the opening 3 adjacent the lower end of the elevator that is controlled by a gate valve 4 vertically slidable in guides 5 and controlled by the handle 6 as shown in Figure 2.

An elongated casing 7 horizontally disposed as shown in Figure 1, projects forwardly of the upper end of the elevator 1 and incloses a horizontal endless conveyor 8 passing over guide pulleys 9 for delivering grain discharged at the upper end of the elevator at the forward end of the casing into the chamber 10 which is a conventional form of feed hopper on grain cleaning machines. The desired discharge of grain from the chamber 10 into the cleaning machine 13 is controlled by the feed gate 15 operated by the handle 16 passing through the end wall 11.

A vertical accumulator bin 17 is located at the forward side of the elevator 1, the open upper end thereof being in communication with the rear end of the casing 7 at the lower side thereof while a rearwardly directed spout 18 at the lower end of the accumulator bin is in communication with the grain receiving hopper 2 by the provision of the opening 19 in the forward side wall of the hopper 2 as shown in Figure 2. The grain carried forwardly by the endless conveyor from the upper end of the elevator to the chamber 10 is regulated in its flow into the machine 13 by the feed gate 15, allowing excess grain to collect in the chamber 10 for a constant supply into the cleaning machine. When the grain in the chamber 10 rises above the level of the lower side of the casing 7, the same is carried rearwardly by the lower part of the endless conveyor and discharged

into the accumulator bin 17 from whence it is delivered through the spout 18 into the grain receiving hopper 2. The grain remains in the accumulator bin until grain in the hopper has been practically exhausted therefrom by the elevator 1 and at which time the opening 19 in the hopper being exposed, the grain from the accumulator bin will gravitationally flow into the hopper and provide a constant supply for the elevator. With a device of this character, it is possible to supply grain to the machine greatly in excess of its normal output with the excess grain automatically returned to the grain receiving hopper for free delivery through the machine and permitting an operator to perform other duties in connection with the operation of the machinery and rendering unnecessary constant supplying of grain to the machine at only its limited capacity of output.

In the form of the invention shown in Figure 3, the endless conveyor is omitted and the grain is caused to flow gravitationally from the upper end of the elevator into the machine. In this form of the invention, the grain receiving hopper 2a is in communication with the elevator 1a and the grain discharged from the upper end of the elevator 1a enters a chamber 10a adjacent the elevator at the rear end of the casing 7a. The flow of grain from the chamber 10a to the cleaner 13a through the passage 12a is controlled by the damper 15a having an operating handle 16a. Excess grain gathering in the chamber 10a flows through the pipe section 20 into the accumulator bin 17a for return through the spout 18a to the grain receiving hopper 2a.

While there are herein shown and described the preferred embodiments of the invention, it is nevertheless to be understood that minor changes may be made therein without departing from the spirit and scope of the invention as claimed.

45 I claim:—

1. In combination with a grain handling machine, an elevator, a grain receiving hopper in communication with the lower end of the elevator, an endless conveyor receiving grain from the upper end of the elevator for discharge into the feed hopper of the machine, and an accumulator bin receiving excess grain by action of the conveyor from the cleaner feed hopper for return to the grain receiving hopper.

2. In combination with a grain handling machine, an elevator, a grain receiving hopper in communication with the lower end of the elevator, an endless conveyor receiving grain from the upper end of the elevator for discharge into the feed hopper of the machine, means for regulating the discharge of grain through the machine, and an accumulator bin receiving excess grain by action of

the conveyor from the machine feed hopper for return to the grain receiving hopper.

3. In combination with a grain handling machine, an elevator, a grain receiving hopper in communication with the lower end of the elevator, an endless conveyor receiving grain from the upper end of the elevator for discharge through the machine, an accumulator bin receiving excess grain by action of the conveyor from the machine feed hopper for return to the grain receiving hopper, the connection between the accumulator bin and grain receiving hopper including a spout on the bin entering a side of the hopper adjacent the bottom whereby grain remains in the bin until the outlet of the spout is exposed, by grain in the hopper flowing into the elevator.

4. In combination with a grain handling machine, an elevator, a grain receiving hopper in communication with the lower end of the elevator, an endless conveyor receiving grain from the upper end of the elevator for discharge through the machine, means for regulating the discharge of grain through the machine, an accumulator bin receiving excess grain by action of the conveyor from the machine feed hopper for return to the grain receiving hopper, the connection between the accumulator bin and grain receiving hopper, including a spout on the bin entering a side of the hopper adjacent the bottom whereby grain remains in the bin until the outlet of the spout is exposed by grain in the hopper flowing into the elevator.

5. In combination with a grain handling machine, an elevator, a grain receiving hopper in communication with the lower end of the elevator, an accumulator bin in communication with the upper end of the elevator, a return spout extending from the lower end of the bin to the hopper, the point of communication between the elevator and bin comprising a feed hopper discharging grain into the machine, and means for discharging excess grain delivered to the chamber into the accumulator bin.

6. In combination with a grain handling machine, an elevator, a grain receiving hopper in communication with the lower end of the elevator, an accumulator bin in communication with the upper end of the elevator, a return spout extending from the lower end of the bin to the hopper, the point of communication between the elevator and bin comprising a feed hopper discharging grain into the machine, means for discharging excess grain delivered to the chamber into the accumulator bin, and means for controlling the flow of grain through the machine.

In testimony whereof I affix my signature.
JOHN W. HOEFLING.
